UNITED STATES PATENT OFFICE.

LOUIS DINGER, JR., OF NEW YORK, N. Y.

RAILWAY-RAIL JOINT.

SPECIFICATION forming part of Letters Patent No. 739,656, dated September 22, 1903.

Application filed June 13, 1903. Serial No. 161,369. (No model.)

To all whom it may concern:

Be it known that I, LOUIS DINGER, Jr., a citizen of the United States, residing at New York, in the county of New York and State 5 of New York, have invented new and useful Improvements in Railway-Rail Joints, of which the following is a specification.

My invention has relation to new and useful improvements in railway-rail joints; and 10 the object is to provide a joint of the character described which will be simple in construction and which will effectually prevent any lateral or vertical movement of the joined ends of the rail-sections with relation to each 15 other and which at the same time will permit the free longitudinal movement of the rails due to contraction and expansion.

The invention consists in the novel construction of the various elements of the invention and their arrangement and aggroupment in operative combination, the novelty 20 of which will be particularly pointed out and distinctly claimed.

I have fully and clearly illustrated my invention in the accompanying drawings, forming 25 a part of this specification, and wherein—

Figure 1 is a perspective view of the meeting ends of two rail-sections which are connected by means of my improved rail-joint. 30 Fig. 2 is a longitudinal vertical central section taken through the rails and joint connecting them. Fig. 3 is a top plan view of the invention. Fig. 4 is a transverse vertical section on the line 4 4 of Fig. 2, and Fig. 35 5 is a transverse vertical section on the line 5 5 of Fig. 2.

Referring to the drawings, 1 1 designate the meeting ends of two rail-sections, which are of the well-known type consisting of a 40 base, web, and tread and in connection with which my invention is employed. The adjacent or meeting ends of these rail-sections are formed in their tread-sections with recesses 2 2, which are shown as being V-shaped in contour and extend longitudinally of the rail for such a distance and are of such a depth as may be desired or required. The rail-sections are also provided with longitudinally-projecting tongues 3 3, which are 45 extensions of the web of the rail and coincide in width therewith, the base of the rails being cut away, as shown at 4 4 in Fig. 2 of

the drawings. Each of the tongues 3 3 is provided with an elongated slot 5, the purpose of which will fully appear hereinafter. 55 6 designates the connecting-block by means of which the ends of the rail-sections are connected. This block comprises a body portion formed with a tread-section 7, the upper surface and sides of which are formed to coincide with the treads of the rail-sections and to span the distance between the treads of said rail-sections substantially as shown in the drawings. The connecting-block is formed at its upper opposite ends with tapering extensions 8 8, which are arranged to be seated in the V-shaped recesses in the ends of the rails, the said extensions being formed to coincide with the contour of the said recess and being of such thickness that when 70 seated in the recesses the upper surface of the treads of the rails and the connecting-block will be flush to provide a smooth riding-surface.

Through the body portion of the connecting-block 6 is formed a longitudinally-extending opening 9, which extends entirely through said block and is arranged to receive the projections 3 3 on the webs of the meeting rail-sections, said sections being secured in position in the connecting-block by means of transversely-arranged headed bolts 10 10, extending through the block from side to side and projected through the elongated slots in the projections on the rail-sections, said slots providing for the movement of the rails due to 85 contraction and expansion. The bolts, as shown, are secured in position by means of the usual nuts 11 11. At its base portion the connecting-block is provided with flanges 12 90 12, which are secured to the tie by spikes 13, whereby the joint is held rigidly in position. It will be seen that the joint-block being rigidly secured to the tie and the projections on the rail-sections being seated in said block 95 and the projections on the block being seated in the recesses in the rails all vertical and lateral movement of the rails with relation to each other will be prevented, but that the rails may be free to move longitudinally without 100 hindrance, the rails not being spiked to the tie.

Having thus described the invention, what is claimed as new is—

1. The combination with the meeting ends

of railroad - rails, each provided with a V-shaped recess in its tread and a projecting web, of a connecting-block provided with V-shaped projections adapted to be seated in 5 the recesses of the rails and an opening to receive the webs of the rails.

2. The combination with the meeting ends of railroad-rails each provided with a recess in its tread and a projection, of a connecting-block provided with projections to be seated in the recesses and openings to receive the 10 projections.

3. The combination with the meeting ends of railroad - rails each provided with a V-shaped recess in its tread and a projecting web portion, of a connecting-block provided with a tread having oppositely-directed V-shaped projections, adapted to be seated in 15 the recesses in the rail, and having an opening to receive the web portions of said rails.

4. The combination with the meeting ends 20

of railroad - rails each provided with a V-shaped recess in its tread and a projecting web portion to form a tongue, said tongues having elongated slots therein, of a connecting-block composing a body and tread portion, said tread being provided with oppositely-directed tapering projections adapted to be seated in the V-shaped recesses in the treads of the rails, the body of the block having a longitudinal opening to receive the tongues on the rails, and base-flanges adapted to be secured to a tie, and transverse bolts extending through the block and the slots in the tongues on the rail. 25

In testimony whereof I affix my signature in presence of two witnesses.

LOUIS DINGER, JR.
